Primary Examiner — Ian Simmons*Assistant Examiner* — Richelle G Shelton*(74) Attorney, Agent, or Firm* — NSIP Law(57) **CLAIM**

The ornamental design for a display screen or portion thereof with a graphical user interface, as shown and described.

DESCRIPTION

FIG. 1 is a front view of a display screen or portion thereof with a graphical user interface showing our new design; and, FIG. 2 is a front view thereof, provided to illustrate an example environment.

The long and short dashed broken line showing of a mobile terminal in FIG. 1 forms no part of the claimed design. The mobile terminal, display screen, and the text/words, numbers, symbols, and images of the graphical user interface shown in broken lines in FIGS. 1 and 2 form no part of the claimed design.

1 Claim, 2 Drawing SheetsFIG. 1

FIG. 2
